PROFILE GRINDING OR POLISHING
MACHINE

Frederic Thomas Dyer and Raymond Herbert Revett, Ipswich, England, assignors to Ransomes Sims & Jefferies, Limited, Ipswich, England, a British company

Application October 16, 1952, Serial No. 315,142

Claims priority, application Great Britain
October 19, 1951

4 Claims. (Cl. 51—93)

1

The invention relates to a profile grinding or polishing machine of the character described in the specification of U. S. Patent No. 2,585,376 and consists in improvements in or modifications of the means for effecting and controlling the operation of the cross feed carriage.

The objects are to ensure smooth and accurate operation by simpler means than a lead screw driven by a variable speed gear box and motor, and also to permit of a greater range and more flexible control of speed variation during feeding, and a rapid return of the cross feed carriage.

The invention consists in the provision of a hydraulic cylinder for advancing and returning the cross feed carriage, and of a control valve, for controlling the supply and exhaust of pressure fluid to and from the hydraulic cylinder, the control valve being operable by hand to start and stop the operation of the cross feed carriage when required, and also operable automatically to stop the operation at the end of each feeding and return stroke of the cross-feed carriage.

A valve is also preferably provided to work in conjunction with the control valve to regulate the flow of exhaust from the hydraulic cylinder during the advancing or feeding stroke of the cross feed carriage for the purpose of regulating the rate of feed.

The control valve is preferably such that it has two exhaust ports for alternate use during the feeding and return strokes of the cross feed carriage, one port being connected with the regulating valve during the advancing or feeding stroke of the cross feed carriage, and the other port being connected with a gate valve or the like permitting of a free flow to a sump during the return stroke of the cross feed carriage to effect a quick return.

The regulating valve is preferably automatically operated by a cam on the cross feed carriage so as to vary the outflow of exhaust fluid during the feeding of the cross feed carriage. The regulating valve is also adapted to be adjusted or set by hand so that the effective area of the exhaust outlet controlled by it can be accurately determined.

In the accompanying drawings:

Figures 1 and 2 are respectively a front and side elevation of a grinding and polishing machine according to the invention;

Figure 3 is a side view of the attachment of the piston rod of the cross-feed hydraulic cylinder to the cross-feed carriage part of which is shown in section;

Figure 4 is a longitudinal sectional elevation

2

of the control valve for the cross feed hydraulic cylinder;

Figures 5 and 6 are respectively a side elevation and a plan of the speed control valve;

Figure 7 is a front sectional elevation of the speed control valve on VII—VII, Figure 6;

Figure 8 is a sectional plan on VIII—VIII, Figure 5;

Figure 9 is a diagrammatic side view of the hand and automatic means for operating the stop and start valve; and,

Figure 10 is a flow diagram.

The machine illustrated by Figures 1 and 2 is of the character described in the specification hereinbefore referred to and for convenience some of the corresponding characteristic parts are indicated by similar reference numerals to those in the drawings accompanying that specification.

Briefly the machine comprises a grinding wheel 1 fixed on a spindle 2 which is mounted to rotate in a bearing housing 3 pivotally supported on trunnions 4 in a crotch 5 adapted to be raised and lowered on a stationary column 8 so as to vary the height of the pivotal support of the grinding wheel spindle. The spindle 2 is normally free to oscillate about its pivotal axis but means are provided for swinging the spindle with its grinding wheel up into an inoperative position at the completion of a grinding operation, and for lowering it again as required.

A work piece to be ground or polished indicated in dotted lines at 35 is clamped on a work table 34 mounted to oscillate on trunnions 36 supported by brackets 37 on a traversing table 38 which reciprocates on slideways 39 and rollers 40 on a cross feed carriage 41.

The work table is tilted up and down by hydraulic cylinders. In the machine described in the specification hereinbefore referred to these were single acting cylinders, but in the present instance double acting hydraulic cylinders 303 are indicated. They are pivotally mounted on trunnions 304 on brackets 305 fixed on the brackets 37, and have piston rods 306 pivotally connected at 307 to levers 308 fixed on the trunnions 36 of the work table 34.

The traversing table 38 is reciprocated by a double acting hydraulic cylinder 42 as described in the specification hereinbefore referred to and during the reciprocations or traversing movements of the table 38, the work table 34 is tilted up and down by the hydraulic cylinders 303 the supply and exhaust of pressure fluid to and from which are controlled by a control valve 311 which

comprises a ported valve casing 313 fitted internally with a piston valve having an operating plunger 339 having a roller 340 running on a cam bar 341. The cam bar 341 is supported on rods 342 carried in guides 343 on the cross feed carriage 41, the rods having rollers 344 on their lower ends running on rails 345 on the machine base 65.

The control valve casing 313 is carried on a bracket 312 sliding up and down in guides on brackets 319 fixed on a cross bar 320 supported at its ends on the brackets 37 on the traversing table 38. The bracket 312 is connected by links 323 to an arm 325 on the work table.

The result is that as the traversing carriage reciprocates to present the work piece on the work table to the grinding wheel, the work table is tilted up and down to maintain the surface to be ground normal to the grinding wheel which makes mutual movements as explained in the specification hereinbefore referred to. The mechanism above described does not form an essential part of the present invention and is more fully described in the specification of co-pending application Serial No. 315,141, filed on even date herewith, and the above brief description is only given for convenience in understanding the character of the machine.

In the U. S. specification No. 2,585,376, mechanism is described for slowly advancing and more quickly retracting the cross feed carriage 41, but improved means for effecting this according to the present invention will now be described.

The cross feed carriage 41 is mounted to slide on slideways 66 on the stationary machine base 65. It is reciprocated on these slideways by a double acting hydraulic cylinder 300 fixed on the base 65. The piston rod 301 of the hydraulic cylinder 300 is attached at its outer end to a bracket 302 fixed on the underside of the cross feed carriage 41. The supply and exhaust of pressure fluid to opposite ends of the cylinder 300 is effected by pipes 371 and 372 connected with a control valve 400. It comprises a valve casing 373, Figure 4, having ports 374 and 375 with which the pipes 371 and 372 are respectively connected. It also has an inlet or supply port 376, and two exhaust ports 377 and 378.

A supply pipe 379 is connected with the port 376, and two exhaust pipes 380 and 381 are respectively connected with the exhaust ports 377 and 378.

A piston valve 382 controls these ports. It protrudes from the ends of the valve casing, and inside the casing it has a central piston 383 for controlling the supply port 376, and two outer pistons 384 and 385 for respectively controlling the exhaust ports 377 and 378.

The protruding ends of the piston valve 382, as explained later on, engage with tappets 386 and 387 which are fixed on a push rod 388, mounted to slide on parts 389 and 390 of the base 65.

The control valve casing 313 is fixed by a bracket 391, Figure 1, to the base 65.

The exhaust pipe 380 is connected to an exhaust regulating valve 392 by which the rate of outflow of pressure fluid can be controlled to vary the speed of the cross feed carriage 41 when advancing under the influence of the hydraulic cylinder 300. The exhaust pipe 381 on the contrary is fitted with an ordinary gate valve 393, Figure 10, so that pressure fluid in the exhaust pipe 381 can flow freely to a sump 190, and consequently allow the hydraulic cylinder 300 to

effect a quick return of the cross feed carriage 41.

The regulating valve 392, which may be conveniently termed a speed control valve, comprises a valve casing 394, Figures 6 and 7, having an inlet port 395 with which the exhaust pipe 380 is connected, and an outlet port 396 connected by a pipe 397 to the sump 190, Figure 10.

A piston valve 398 has a piston 500 for controlling the outlet port 396 and a piston 399 for balancing internal pressure only.

The piston valve 398 protrudes from both ends of the casing 394 and is urged upwardly by a helical spring 401. The upper end of the piston valve 398 is in contact with a lever 402 which has a fulcrum pin 403 at one end and a roller 404 at the other end for engagement with a cam 405 which is fixed on the cross feed carriage 41 (Figure 2). The fulcrum pin 403 is supported in a bearing bracket 393 fixed on a plate 411 which is secured to the machine base 65. The valve piston 500 has a slot 406 which tapers downwardly so that as the piston valve 398 is depressed the amount to which the slot 406 is opened to the outlet port 396 is increased. In order to enable the effective area of the slot to be varied or adjusted accurately by hand, and thereby to regulate the outflow of exhaust fluid and consequently regulate the feeding movement of the cross feed carriage 41, means are provided for partially rotating the piston valve 398 relatively to the casing 394, such means being adapted to hold the piston valve 398 against rotation after adjustment and yet allow it to slide up and down in the casing.

These regulating means comprise a lever 407 on the lower end of the piston valve 398. The lever has a key 408 which enters a slot 409 in the piston valve 398, the slot being deeper than the key so that the piston valve can rise and fall relatively to the key.

The lever 407 is mounted in a forked bracket 410 which is fixed to plate 411 on which the casing 394 of the regulating valve 392 is also mounted.

The outer end of the lever 407 is forked and supports a pin or trunnion 413. A rod 414 has one end fixed in the trunnion 413 and is screw threaded to receive a regulating nut 415 which has a cylindrical extension 416 mounted to rotate in a bracket 417 fixed on the plate 411. The nut 415 is prevented from sliding by balls 418 which engage in a groove 419 in the nut, the balls being held in position by plugs 420, Figure 7.

Rotation of the nut 415 in one direction or the other effects relative rotation of the piston valve 398 in the casing 394 and consequently alters the position of the slot 406 in the piston 500 relatively to the outlet port 396 and thereby determines the effective area of the slot for the outflow of exhaust fluid.

The plate 411 is fixed to the machine base 65 and, as shown in Figure 2, in such a position that the roller 404 on the lever 407 can be operated by the cam 405 to regulate the flow of exhaust fluid from the control valve 400 during the relatively slow advancing or feeding stroke of the cross feed carriage 41.

As mentioned above, the exhaust pipe 380 is only used during the advancing or feeding stroke of the cross feed carriage 41 the other exhaust pipe 381 being used during the return stroke of the cross feed carriage when the free flow through the gate valve 393 is possible to allow a quick return of the carriage.

As shown more clearly in Figure 9, a hand op-

erating lever 421, pivoted to the base 65 on a pivot pin 423 and pivotally connected by a pin 422 to the push rod 388, enables the control valve 400 to be operated by hand at any time to effect reversal of the cross feed carriage.

Reversal is effected by means now to be described.

The push rod 388 has a collar or abutment 146 fixed on one end of it and an intermediate abutment 346 clamped in any desired position.

A tappet 143 fixed on the cross feed carriage 41 strikes the abutment 346 as the carriage reaches the end of its return stroke.

A push rod 134 slides in guides 135 fixed to the front of the base 65, and in the guide 390 fixed at the rear of the base. It has collars 136 and 137 and springs 138 for holding it in a normal position. It has a tooth 139 for engagement with two rather widely spaced teeth 140, 141, on a rocker 142 oscillated by a lever 124. The push rod 134 has a collar 142 clamped on its rear end for engagement with the collar 146, and a collar 342 clamped in any desired position for engagement by the tappet 143 when the cross feed carriage reaches the end of its advancing or feeding stroke.

Incidentally the lever 124 operates a stop and start valve, and a lever 111 operates a valve controlling the hydraulic mechanism for raising and lowering the grinding wheel, these valves being also fully described in the U. S. specification No. 2,585,376.

In operation of the machine, assuming that the cross feed carriage 41 has completed an outward or return stroke, the tappet 143 will have engaged the abutment 346 and shifted the push rod 388 so that the tappet 387 will have shifted the piston valve 382 to the neutral position and the cross feed carriage will stop. When it is desired to make an inward or operative stroke, the lever 421 is pulled so that the tappet 387 will shift the piston valve 382 so that the exhaust port 378 will be closed by the valve piston 385, the exhaust port 371 will be uncovered by the valve piston 384 and the inlet port 376 will be uncovered by the valve piston 383 to allow pressure fluid to pass to the port 375 but will prevent pressure fluid passing to the port 374. Consequently pressure fluid can pass by the pipe 372 to one end of the hydraulic cylinder 300, and exhaust fluid from the opposite end by the pipe 371 via ports 374 and 377 and exhaust pipe 380 regulating valve 392 and pipe 397 to the sump 190, with the result that the piston rod 301 of the hydraulic cylinder will begin to advance the cross feed carriage 41.

At the beginning of this advancing stroke of the cross feed carriage 41 the lever 402 will be depressed by the end of the cam 405, and be holding the piston valve 398 down so that the valve piston 500 will be in a position to allow fluid to pass fairly freely through the slot 406 to the exhaust port 396 and thence through the pipe 397 to the sump 190.

As the cross feed carriage advances sufficiently to allow the roller 404 to rise up the upwardly curved part of the cam 405 the spring 401 raises the piston valve 398 and the valve piston 500 moves up and the slot 406 offers a more restricted passage to the flow of exhaust fluid so that the speed of advance of the cross feed carriage, or rate of feed, is slowed down.

As the roller 404 rides down the downwardly curved part of the cam 405 the lever 402 depresses the piston valve 398 of the regulating valve so

that the exhaust flow through the slot 406 is increased and consequently the rate of feed or advance of the cross feed carriage 41 is increased. The reason for varying the rate of feed by the varying curvature of the cam 405 is that a work piece such as a mould board varies in length due to its peculiar shape and that the rate of feed of the cross feed carriage should be slower when the traversing carriage is making long strokes and quicker when it is making short strokes.

The shape of the cam 405 is therefore determined to suit the shape of the work piece to be ground.

When the cross feed carriage reaches the end of its advancing or feeding stroke the tappet 143 strikes the collar 342 on the push rod 134 and moves it so that the collar 142 strikes the collar 146 and shifts the push rod 388 whereby the tappet 386 will shift the position of the piston valve 382 of the control valve 400 back into the neutral position and thus stop the feeding of the cross feed carriage. To bring the cross feed carriage back to the outward position, the lever 421 is pushed inwardly, thereby pushing the push rod 388 towards the rear of the machine. As the push rod 388 moves, the tappet 386 will shift the position of the piston valve 382 so that the pressure fluid will pass through the pipe 371 to the hydraulic cylinder and fluid is exhausted from it via pipe 372, pipe 381 freely through the gate valve 393 to the sump 190.

At the same time the valve piston 384 closes the exhaust port 377. Owing to the free flow of exhaust the return stroke of the cross feed carriage is much quicker than the advance or feeding stroke.

In Figures 2 and 9 the push rod 134 is shown connected by a chain 144 to an electric solenoid 154, the chain passing over a guide pulley 145. As described in Patent No. 2,585,376, in case of an emergency, a switch is closed whereupon the solenoid 254 is energized and pulls the push rod 134 which moves the rocker 142 to operate the stop and start valve and thereby cut off the supply of pressure fluid. In the present instance, this operation of the push rod 134 also moves the piston valve 382 of the control valve 400 to a neutral position.

We claim:

1. A grinding machine of the character referred to for grinding mould boards of plough bodies and other articles of varying profile, said machine comprising a base, journal means pivotally mounted on said base, a spindle journaled in said means with its axis substantially perpendicular to the axis of the pivotal mounting of said journal means, a grinding wheel mounted on said spindle, a cross-feed carriage mounted on said base for movement substantially axially of and toward and away from said grinding wheel, a traverse table mounted on said carriage for traverse movement transverse to the motion of said carriage, a work table pivotally mounted on said traverse table for tilting about an axis substantially perpendicular to the axis of said wheel, means on said carriage and connected to said traverse table for reciprocating said traverse table relative to said grinding wheel, means on said traverse table and connected with said work table for tilting said work table during reciprocation of said traverse table, a double acting hydraulic cylinder mounted on said stationary support and having a piston rod connected with cross feed carriage for reciprocating said cross feed carriage toward and away from said grinding wheel, means for controlling

the supply and exhaust of pressure fluid to said hydraulic cylinder comprising a reciprocatory control valve of the multi-ported and multi-piston type, said control valve having two exhaust pipe connections for alternate use respectively during the forward feeding stroke of the cross feed carriage and the return stroke thereof, one of said exhaust pipe connections being free to exhaust to permit a quick return of said cross-feed carriage, a cam on the cross feed carriage, and a speed regulating valve on said base and operated by said cam and connected with the other exhaust pipe connection which is used during the forward feed stroke to ensure a slow continuous feed of said cross feed carriage.

2. A grinding machine as specified in claim 1, said speed regulating valve comprising a valve casing having an exhaust port, a reciprocatory valve piston in said casing for controlling said port, said valve piston having a tapered passage for cooperation with said port, and a spindle protruding from said valve casing, a spring for pressing said spindle upwards, a lever for depressing said spindle downwards, said lever having a roller, a curved cam on the cross feed carriage for engaging with said roller, and means for rotating said spindle for varying the relation of said tapered passage and said cooperating exhaust port for regulating the effective area of exhaust.

3. A grinding machine comprising a base, a 30 grinding wheel journaled on said base, a cross-feed carriage mounted on said base for movement toward and away from said wheel in a direction substantially axially of said wheel, a traverse table mounted on said carriage for traverse movement transverse the movement of said carriage, a work table for supporting a work piece in position relative to said grinding wheel, said work table being pivotally mounted on said traverse table for tilting movement about an axis substantially perpendicular to the axis of said wheel, hy-

draulic cylinder means on said base and connected with said cross-feed carriage for advancing and retracting said carriage toward and away from said wheel, a control valve for said hydraulic cylinder means and including a valve body and a valve member movable in said body, means between said cross-feed carriage and said valve member for actuating said valve member upon completion of each stroke of movement of said cross-feed carriage, a cam on said cross-feed carriage, and cam following means on said base engageable with said cam and connected with said control valve to regulate the speed of fluid flow through said valve in accordance with the particular portion of the stroke of movement of said cross-feed carriage.

4. A grinding machine as defined in claim 3 wherein said control valve has two exhaust ports respectively opened by said valve member during the advancing and retracting strokes of movement of said carriage, said port that is open during the retracting stroke of said carriage being free to exhaust to permit a quick return of said carriage, and said cam following means comprises a cam follower actuated speed regulating valve connected with said port which is open during the advancing stroke of said carriage to regulate the speed of forward movement of said carriage.
